UNITED STATES PATENT OFFICE.

ALEXANDER B. WAY, OF LYNN, MASSACHUSETTS, ASSIGNOR TO LEWIS A. WAY, OF PITTSBURGH, PENNSYLVANIA.

MATERIAL FOR THE TREATMENT OF HYDROCARBONS.

No Drawing.

Application filed March 19, 1924. Serial No. 700,382.

This invention relates to a material for treating hydrocarbons to demulsify the same and generally improve their qualities.

This material constituting the subject matter of the present invention is susceptible of use in the treatment of hydrocarbons of numerous grades and of varying condition.

Oils of the grades used in oil burners and the like are especially subject to separation of their heavier components when permitted to stand in containers for storage or transportation, or in service tanks for supplying the fuel to the point of their combustion. This separation usually results in the collection of a slime, comprising heavy sludge, separated carbon, or other relatively dense substances, at the bottom of the tank or container. Such condition results in the loss of combustible material, and also in the fouling of cleaning screens and meters during utilization of the oils.

Any oil when stored or transported tends to receive and form an emulsion with water, which may leak into the tank or container, be absorbed from the moisture of the atmosphere, or enter the body of the oil at some preliminary stage during its production or treatment. Such emulsion tends to prevent the redissolution of heavier separated components of the oil, because of the formation of the minute globules of the emulsion. The surface tension of such globules prevents their breaking up to release the oil, and prevents redissolution of the separated heavier components of the oil.

One object of the present invention is therefore to provide a material which when added to a hydrocarbon oil serves to reduce the surface tension of the globules of any emulsion present, and permits both the removal of the water of such emulsion and the redissolution of separated heavier components of the oil.

Another object of the invention is to provide a material capable of producing the above effect without the necessity for raising the temperature of the oil to such point as to cause the loss of any portion or components thereof through distillation or coking.

Certain grades of oil, moreover, which are incapable of combustion in burners or the like because of their thickness and lack of fluidity, may be rendered fluid and usable by

reducing their viscosity with the material of the present invention. Likewise the heaviest tars may be broken up by treatment with the material, and rendered sufficiently fluid to permit their removal from storage tanks and containers.

Lubricating oils may be rendered more efficient by treatment with the material of the invention.

A probable explanation of the improvement in the quality of lubricating oil lies in the fact that the material causes the oil to assume the state of a true solution. Even relatively small quantities of the oil, when allowed to stand, tend to stratify. In such stratified condition the heavier components of the oil are not in a true solution in the lighter components, but are rather in a colloidal or semi-colloidal condition. The material of the present invention serves to change the colloidal system to one of true solution, thereby lowering the viscosity of the oil. It will be readily seen that this function is a complement to the function of demulsifying an emulsified oil. Smaller quantities of an oil of given viscosity may therefore be employed to provide an adequate lubricating film, and the life of the lubricant is increased. Cylinder oil for internal combustion engines, when treated with the material, causes less deposit of carbon than when untreated and has less tendency to thicken and gum in cold weather than untreated oil of equal lubricating value but greater viscosity.

When utilized in a cracking still for the production of gasoline or other light hydrocarbon products, the addition of the material of the present invention serves to reduce the end point of the gasoline of any particular specific gravity. That is it lowers the temperature necessary to pass over gasoline or other products of a given gravity. Conversely it diminishes the formation of undesirable end products, such as petroleum coke.

Such effect may also be attributed to the fact that the material diminishes the vapor tension of the hydrocarbons.

A specific formula for the material may be given as follows: Naphthalene ($C_{10}H_8$) by volume 95%, nitrobenzol ($C_6H_5NO_2$) by volume 5%.

In this formula the naphthalene, which is

a crystalline hydrocarbon, absorbs the nitro-benzol, which is in the condition of a heavy oil, to produce a single and apparently homogeneous material.

- 5 Such solid mixture may be desirably in divided form. To secure such form the naphthalene is preferably cut and screened, and a portion thereof further granulated prior to the incorporation of the nitro-benzol.
- 10 In practice it is found convenient to use approximately seventy-five parts of the flake naphthalene to twenty-five parts of the granulated naphthalene.
- 15 If the mixture is to be employed to produce the breaking up and redissolution of a heavy slime, such as sludge or tar, such sediment is first covered with a relatively large volume of oil in fluid condition, and the treating mixture added to this initial hydro-
- 20 carbon mixture. With such initial hydrocarbon the treating material is preferably added in a quantity of from 0.5 pound to 1.5 pounds to each 500 gallons of the mixture of sediment and oil. This mass, con-
- 25 sisting of the sediment, oil, and treating mixture is subjected to gentle heating, and maintained at a temperature of from one hundred degrees Fahrenheit to two hundred degrees Fahrenheit for a period of from one
- 30 hour to eighteen hours. The duration of the treatment depends upon the nature of the initial hydrocarbon to be treated, the rate of dispersion of the treating material through this initial hydrocarbon, and the length of time required to exhaust the treating ma-
- 35 terial.

When the treating material has been exhausted, another charge may be added, and the gentle heating continued until exhaustion of such second charge. In certain instances a third treatment may prove desirable.

If an oil having no appreciable quantity of sediment associated therewith is to be treated simply to demulsify such oil and to generally improve its qualities, the general nature of the treatment is identical with that given above. In such case, however, a single charge of the mixture is generally sufficient to produce the desired result. The quantity of the mixture with relation to the volume of the initial hydrocarbon to be treated may also be greatly reduced.

In either of the cases noted above, water separated by the demulsification of the oil is drawn off prior to use of the oil.

If an oil is to be treated to generally improve its qualities, without the necessity for demulsification of such oil, the quantity of the mixture employed may be still further reduced.

Not only the quantity of the mixture employed, but also the relative proportions of its ingredients, may be desirably varied in accordance with the work to be done. Thus for the breaking up of heavy tars, to increase

their fluidity, one pound of the mixture is preferably added for each two hundred and fifty to three hundred gallons of the tar; and the nitro-benzol content may be increased to as much as ten per cent by volume of the en- 70 tire mixture.

To consider the different ingredients of the mixture, the nitro-benzol (or its equivalent) performs the chief active function in breaking down the globules of an emulsion, decreasing the vapor tension of a body of hydrocarbon, and diminishing the viscosity thereof. The naphthalene (or its equivalent) assists to some extent in performing these functions, and also serves as a convenient carrier for the other ingredients, whereby they may be conveniently stored and transported and may be distributed through the hydrocarbon body to be treated. 75

As to equivalent, or substitute, substances 80 in the mixture, anthracene ($C_{14}H_{10}$) which is a crystalline hydrocarbon resembling naphthalene in its physical properties, may be used to take the place of the latter.

As an equivalent for the nitro-benzol, another nitrated member of the aromatic series of hydrocarbons, such as nitrotoluol ($C_6H_4CH_3NO_2$) may be employed.

Whereas these alternative substances serve to impart the desired useful properties to 95 the mixture, the substances included in the formula given above are preferred because of the fact that they are in more common use or because of the fact that they are more readily produced on a commercial 100 scale.

It is also possible to employ nitro-naphthalene or nitro-anthracene, which are themselves nitrated compounds of hydrocarbons derived from the same source as the aromatic series of hydrocarbons, namely from the distillation of coal. These compounds may either one be used with either the nitro-benzol or nitro-toluol of the formula. 105

Favorable, though less satisfactory, results have been obtained by using either nitro-naphthalene or nitro-anthracene alone.

Benzaldehyde may be used to replace the nitro-benzol or nitro-toluol, though not with wholly satisfactory results. Mirbane may 115 also be similarly used. It should be noted that this oil, though an essential oil of vegetable origin, closely resembles nitro-benzol both in chemical structure and in characteristics.

It will be seen from the above that the particular substances noted in the formula, as well as the relative proportions of such substances, may be varied within the scope of the disclosure and the appended claims 120 without departing from the spirit of the present invention.

It is also to be noted that all substances noted are organic compounds. When used for the treatment of hydrocarbons, they 125

therefore leave no incombustible residue as do inorganic treating materials such as aluminum chloride, and the like.

What I claim is:

- 5 1. As an article of manufacture for the treatment of hydrocarbons to demulsify the same and increase their fluidity, a material comprising naphthalene, and a nitrated aromatic hydrocarbon in the primary stage of
- 10 10. nitration associated with the naphthalene as the principal active agent of the material.
- 15 2. As an article of manufacture for the treatment of hydrocarbons to demulsify the same and increase their fluidity, a material comprising naphthalene and nitrobenzol associated with the naphthalene as the principal active agent of the material.

3. As an article of manufacture for the treatment of hydrocarbons to demulsify the same and increase their fluidity, a material 20 comprising an aromatic hydrocarbon in crystalline form, and a nitrated aromatic hydrocarbon in the primary state of nitration associated with said crystalline hydrocarbon.

4. As an article of manufacture for the treatment of hydrocarbons to demulsify the same and increase their fluidity, a material 25 comprising an aromatic hydrocarbon in crystalline form, and nitrobenzol associated 30 with said crystalline hydrocarbon.

In witness whereof, I hereunto set my hand.

ALEXANDER B. WAY.
